UNITED STATES PATENT OFFICE.

EUGENE F. NISSEN, OF ALAMEDA, CALIFORNIA.

SAFETY-CONTAINER.

1,340,553.

Specification of Letters Patent. Patented May 18, 1920.

Application filed December 12, 1918. Serial No. 266,370.

To all whom it may concern:

Be it known that I, EUGENE F. NISSEN, a citizen of the United States, residing at Alameda, in the county of Alameda and State 5 of California, have invented new and useful Improvements in Safety-Containers, of which the following is a specification.

This invention relates to a safety container.

10 It is the principal object of this invention to provide a fabric or paper container within which articles may be placed and held in a manner to prevent them from being removed without mutilating some portion of the container and thus insuring detection, the present structure being designed to form a neat package when a few articles or documents are placed therein and to be expanded when desired to readily accommodate a 15 large number of documents, at all times being fastened by a seal of one size, thus not only conserving the material used to seal the envelop but also insuring that the documents within the envelop will be held in a 20 manner to prevent unauthorized access thereto and accidental bursting of the container in transit.

The present invention contemplates the use of a blank forming a body panel, a back 30 panel integral therewith, flaps at the opposite sides of the body panel and a closure flap for the end, said panels and flaps being adapted to be folded to form a smooth front and back panel and collapsible edges or 35 gussets, the panels and flaps overlapping and uniting with each other in a manner to preclude the possibility of access to the container.

40 The invention is illustrated by way of example in the accompanying drawings, in which—

Figure 1 is a view in plan illustrating the blank of the container and further indicating in dotted lines the scoring marks for the 45 various folds.

Fig. 2 is a small perspective view illustrating the completely formed container in its open position.

Fig. 3 is a view similar to Fig. 2 disclosing 50 the container as sealed.

Fig. 4 is a fragmentary view in perspective illustrating the lower portion of the container as partially formed and folded.

Fig. 5 is a fragmentary view disclosing a

part of the container blank shown in Fig. 4 55 and further illustrating the initial step in forming the gusset in the lower end of the container.

Fig. 6 is a perspective view similar to Fig. 5 showing the manner in which the back 60 panel is folded into the gusset at the bottom of the container.

Fig. 7 is a view illustrating a continuation of the forming process disclosing the upward fold of the overlapping flaps at the 65 back of the container.

Fig. 8 is a view in perspective illustrating the manner in which the back panel is folded upwardly over the overlapping flaps 70 of the container and the bottom of the gusset completed.

Fig. 9 is an enlarged fragmentary view in section disclosing the lower end of the container as completely formed.

Fig. 10 is a fragmentary view in perspective 75 illustrating the upper end of the container and indicating by dotted lines the scoring marks for folding.

Fig. 11 is a view in perspective illustrating the manner in which the upper end of 80 the blank is folded to form gussets.

Fig. 12 is a view in vertical section disclosing the upper end of the container and the fold in the sealing flap.

Fig. 13 is a view in section disclosing the 85 gusset in the opposite side edges of the container.

Fig. 14 is a view in section illustrating a fragmentary portion of the top of the container when filled and the gussets 90 completely distended.

In the drawings, 10 indicates a blank from which a container 11 is formed. This blank may be made of fabric or paper and cut as indicated in Fig. 1 of the drawings. 95 When formed a rectangular body panel 12 will be produced bound by the dotted lines A, B, C and D. Formed as a continuation of one end of this panel is a closure flap 13 which is of a width equal to the distance between the lines B and D and extends from the line A to its outer marginal edge. Extending from the opposite end of the body panel is a back panel 14. This panel is of a width equal to the width of the body 100 panel and of a length equal to that of the body panel plus the distance between the scoring line C and a scoring line E, which

distance represents the thickness of the container when its edge gussets are completely distended.

Formed at opposite sides of the body panel are outer and inner side flaps 15 and 16. These flaps are rectangular in shape and are of a length equaling that of the body panel plus the thickness of the container when filled. The edges of these flaps at 10 one end terminate on a line representing a continuation of the scoring mark E upon the back panel, and at the opposite end along the line represented by a scoring mark F on the closure flap. The portion 15 of the side flaps extending beyond the scoring lines at the ends of the body panel are separated from the back panel 14 and the sealing flap 13.

Scoring marks G and H are formed the 20 length of the side flaps 15 and 16 respectively, and are parallel with the scoring marks B and D, which represent the opposite sides of the body panel 12. The marks G and H are separated from the marks B and D, respectively, a distance equal to the thickness of the container when filled, this distance corresponding to the distance between the end scoring marks A and F and the marks C and E. Intermediate fold 25 marks I are made midway between the body panel and the scoring marks G and H and thereby form gussets along the opposite sides of the container. Similar marks J are made between the ends of the body panel 30 and the scoring marks E and F to form gussets at the opposite ends of the container. Prior to folding the blank the flap 15 is gummed along its edge portion, while the back panel 14 is likewise gummed along 40 its opposite side edges, as indicated at 18 and 19.

The initial step in forming the container is to bring the side flap 15 over the flap 16 and cause the contiguous faces of these two flaps to be glued together by the gummed 45 surface 17, thus forming a rectangular compartment 20, as indicated in Fig. 4. After the flaps have been thus glued their lower ends are folded along the oblique scoring lines K which terminate at the gusset fold lines I and there intersect short fold lines L.

Referring to Fig. 5, it will be seen that this operation will cause the flaps to be folded down upon themselves and thereafter produce a fold in a single plane across the bottom of the container, this last-named fold being represented by the portion of the flaps subtended by the scoring lines L and the portion of the scoring line K extending 50 from the lines C to their point of intersection with the lines L. The body panel 12 is then folded on the line C and creased on the line J, this creased portion being folded 60 into the gusset previously formed by the side flaps. The gummed surfaces 18 and

19 of this body panel will adhere to the gusset fold of the side flaps and act to produce a completely sealed gusset extending entirely across the end of the container, as shown in Fig. 6.

The folded and glued lower ends of the side flaps are then folded upwardly and outwardly along their scoring marks C, as shown in Fig. 7, and thereafter completely concealed beneath the back panel 14 as it 70 is brought up over the flaps 15 and 16 and fastened thereto by the adhesive material at 18 and 19. The compartment 20 will still be rectangular in shape, as shown in Fig. 10, at which time the upper ends of the flaps 80 15 and 16 are folded along their inclined scoring marks K to bring the portion of each flap adjacent the body panel inwardly and in a single plane extending across the open mouth of the compartment. The flaps 85 are both folded along the scoring marks I to form an upper gusset, after which the central portion formed by the two flaps is folded inwardly on the line A and outwardly along the line J, thus completing a 90 gusset at the top of the container. The closure flap 13 is then creased inwardly along the line A and outwardly along the line J, thereafter being folded over the back panel 95 along the scoring line F.

It will be observed that a straight gusset will thus be formed entirely across the opposite ends of the container and that similar gussets will be formed along the opposite sides of the container, as the portion of 100 each of the flaps 15 and 16 is creased inwardly along the scoring marks I and folded down so that on one side the scoring marks B and G will coincide and on the other side the scoring marks D and H will 105 register. The edges formed along the marks B and D will define the sides of the body panel 12, while the edges formed along the marks G and H will represent a width equal to the width of the body panel and corresponding to the width of the back 110 panel 14. After the forming operation a metallic fastener 21 may be applied to the back of the container and may be fastened through the back panel and the flaps 15 and 115 16. A plurality of eyelets 22 are placed near the end of the flap 13 and are designed to separately register with the fastener 21 when in its folded and closed position, thus making it possible to compactly seal the 120 closure flap in place, regardless of the number of articles or quantity within the container. In commercial use, the fastening members may be covered by a wax seal 23, after which the imprint of a mercantile 125 association may be affixed thereupon.

It will therefore be noted that the various parts of the container are fastened together by gumming the blank along the three fields 17, 18 and 19 and by sealing the 130

flap 13 at the one point by the seal 23. When documents or other valuables have been placed within the container thus formed and thereafter sealed, as indicated, 5 it will be practically impossible to remove these articles without materially multilating the walls of the container. In the event that the walls are steamed, it might be possible to separate a back panel 14 from the 10 folded sides of the flaps 15 and 16. However, after this had been accomplished it would still be necessary to loosen the side flaps as held by the gummed surface 17. As these flaps are completely covered by the 15 panel 14, this steaming operation would be difficult. Assuming, however, that the attempt was successful, it would then be quite a problem to reach beneath the back panel 14 and between the separated side flaps 15 20 and 16 to remove the articles from within the compartment and around the edge of the flap 16.

The container here disclosed will therefore be decidedly simple in its construction 25 and will practically preclude the possibility of access to the contents thereof without breaking the seal, at the same time being easily made from a simple blank and easily sealed without the use of a large quantity of 30 sealing wax.

Having thus described my invention,

what I claim and desire to secure by Letters Patent is:

A safety envelop formed of a single blank of material including a central rectangular body panel, a rectangular back panel emanating from one end of the body panel, a flap panel emanating from the other end of the body panel, rectangular shaped side panels emanating from the sides of the 35 body panel, portions of equal width on said emanating panels contiguous the four sides of the body panel being scored each in three parallel lines to form sides of the envelop with gussets, the extreme outer upper and 40 lower corner portions of the side panels being scored so that they are adapted to be folded and lie, the upper beneath the top gusset to reinforce the same, and the lower between the back panel and the adjacent 45 50 folded portions of the side panels when the envelop is formed, the outer edge portion of one side panel being gummed, and the opposite side edges of the emanating back panel being likewise treated.

In testimony whereof I have hereunto set my hand in the presence of two subscribing witnesses.

EUGENE F. NISSEN.
